ELECTRIC SWIVEL

Everette J. Heiner, Fresno, Calif., assignor of one-third to Harry Cleason and one-third to Louis J. Heiner

Application February 13, 1942, Serial No. 430,734

1 Claim. (Cl. 173—324)

This invention relates in general to an improved electrical conductor unit, and in particular the invention is directed to, and it is my principal object to provide, an electrical conductor unit which includes a pair of cooperating assemblies arranged together for relative rotation whereby when the unit is coupled, for example, between an electric cord and current outlet, or between the cord and an electric appliance, the appliance to which the cord leads may rotate without kinking and twisting the cord, and which otherwise frequently results in short-circuiting or breaking thereof.

A further object of the invention is to provide an electrical conductor unit or electric swivel which includes relatively rotatable assemblies which cooperate to conduct electricity through the unit without interruption or fluctuation; the unit including a novel collector ring arrangement.

A further object of the invention is to produce a simple and inexpensive device and yet one which will be exceedingly effective for the purpose for which it is designed.

It is understood, of course, that while the conductor unit or electric swivel may be employed as a separate unit connected with an electric cord at either end or interposed therein, or arranged with one assembly of the unit fixed on the appliance or a current outlet box, the unit—for the purpose of illustration—is here shown as embodied in a prong-type electric plug of the type adapted for connection with the free end of an electric cord.

These objects I accomplish by means of such structure and relative arrangement of parts as will fully appear by a perusal of the following specification and claim.

In the drawing similar characters of reference indicate corresponding parts in the several views.

Figure 1 is an enlarged elevation of the conductor unit.

Figure 2 is an enlarged sectional elevation of said conductor unit.

Referring now more particularly to the characters of reference on the drawing, the numeral 1 indicates a cylindrical body having an internal chamber 2 opening to one end of the body; said body being fitted with a cap 3 having an axial opening 4 therethrough. The opening 4 communicates with chamber 2 but is of substantially less diameter. Both the body 1 and the cap 3 are of dielectric material and may be secured together in any suitable manner.

Annular metallic collector rings 5 are fixed

5 within the chamber 2 of body 1 in spaced and insulated relation axially of said body. Spaced prongs 6 are mounted on and project from the end of the body opposite cap 3, these prongs 6 extending into the body, and one being electrically connected with the adjacent one of the collector rings 5 as at 7, while the other prong is connected with the other collector ring by means of an embedded contact strip 8 formed integral with said prong and which said strip at its free end frictionally engaged said other collector ring.

10 A sleeve 9 of dielectric material projects in clearance and freely rotatable relation into the chamber 2 of body 1 through opening 4 in cap 3, said sleeve terminating short of the bottom of the chamber.

15 Within the chamber 2 the sleeve 9 is fitted with a pair of metallic annular collector rings 10 disposed in axially spaced insulated relation and corresponding to and facing rings 5. Each of the rings 10 is formed with an annular groove or race 11. A circular row of steel balls 12 ride in said races in rings 10 and also ride against rings 5. It will thus be seen that with the above arrangement the sleeve 9 is supported for rotation relative to the body 1. In order to prevent undesired axial displacement of the sleeve 9 relative to body 1, the collector rings 5 at their outer edges are formed with annular inturned flanges 13 which prevent the adjacent row of balls 9 from displacing any substantial distance axially of the body.

20 25 30 35 Within the chamber 2 the sleeve 9 is fitted with a pair of metallic annular collector rings 10 disposed in axially spaced insulated relation and corresponding to and facing rings 5. Each of the rings 10 is formed with an annular groove or race 11. A circular row of steel balls 12 ride in said races in rings 10 and also ride against rings 5. It will thus be seen that with the above arrangement the sleeve 9 is supported for rotation relative to the body 1. In order to prevent undesired axial displacement of the sleeve 9 relative to body 1, the collector rings 5 at their outer edges are formed with annular inturned flanges 13 which prevent the adjacent row of balls 9 from displacing any substantial distance axially of the body.

The electric cord 14 to which the electric

swivel is connected extends into the sleeve 9

from its outer end, the wires 15 of said electric

cord being separated within the sleeve and pass-

ing through small ports 16 therein to separate

connection with the collector rings 10.

40 By virtue of the above described construction, the electric swivel functions to permit of rotation of the cord 14 without interrupting the flow

of current or causing fluctuation thereof, and

the cord does not kink or twist for the reason

45 that any torque therein is immediately relieved.

The above described electric swivel will be

found exceedingly useful in conjunction with the

cords of telephones, vacuum cleaners, electric

irons, electric toasters, or any other electric

50 cords.

While the principal embodiment is a two-wire

electric swivel, the device obviously can be con-

structed to accommodate a different number of

wires.

55 From the foregoing description it will be read-

ily seen that I have produced such a device as substantially fulfills the objects of the invention as set forth herein.

Having thus described my invention, what I claim as new and useful and desire to secure by Letters Patent is:

An electric swivel comprising an insulation sleeve having a two-wire electric cord therein, a pair of annular metal ball bearings each including an inner race and an outer race, the inner races being fitted on the sleeve adjacent one end in spaced and non-axially movable relation, an insulation ring on the sleeve between and engaging the inner races to maintain the bearings spaced, one wire passing radially through the sleeve and engaging one inner race while the other wire likewise passes through the sleeve and engages the other race, an insulation

body forming a cup initially open at one end into which the outer races fit, the sleeve projecting from the open end of the body, an insulation spacer ring in the body between and 5 engaging the outer races, one outer race engaging the bottom of the cup, electric connection elements embedded in the body and exposed at the closed end thereof, one element extending to and engaging one outer race and the other 10 element extending to and engaging the other outer race when the bearings are disposed in the cup, and a cap fitted on the body over its open end and about the sleeve, said cap engaging the outer race of the adjacent bearing whereby axial 15 displacement of both bearings and the sleeve is prevented.

EVERETTE J. HEINER.
